SIGNALING APPARATUS

Otto Kraus, Bad Liebenstein, Germany

Application March 20, 1931, Serial No. 524,151
In Germany September 27, 1929

2 Claims. (Cl. 177—329)

This invention relates to signaling apparatus specially adapted for indicating the direction of a road vehicle and provided with a signal arm, capable of being removed from its case. Such apparatus of well known construction have the disadvantage that the indicating pointer or beckoning arm, and the electro-magnetic coil, and other parts can only be difficultly removed or interchanged.

10 According to the present invention the signal arm and the electromagnetic coil form an interchangeable part which is arranged in its case in such a manner that, after disconnecting this part from the case, the electrical connections are simultaneously interrupted. One feature of the invention resides in the fact that at the inner wall of the direction indicating apparatus is arranged an insulated conducting rod one end of which leads to the electromagnetic coil and is formed as a part which is resilient in itself for the purpose of firmly pressing against the contacts of the coil. A further feature of the invention resides in a plug-contact arranged on the case to which contact leads the conducting rod referred to. A further feature of the invention resides in a locking means, for instance an adjusting screw by which the signal arm and the support carrying the electromagnetic coil are connected with the case. For facilitating the removal of the support carrying the pointer and the coil the said support is suitably fixed in the case against the action of a spring which, due to its tension, after loosening the fixing member, pushes the support out of the case.

35 The invention is represented by way of example in the accompanying drawing in which shows Fig. 1 a side elevation of a direction indicator the signal arm being removed

Fig. 2 a side elevation of the direction indicator, and

Fig. 3 a longitudinal section of the direction indicator.

The signal arm 2 is fastened to a shaft 1 which is pivotally mounted in two ears 4 rectangularly bent off from the plate 4'. The said plate 4' and the plate 4'' of the coil are made in one piece. An ear 11 forming an abutment projects from the plate 4' and an intermediate member 12, in the normal position of the pointer 2, rests upon said ear 11 thereby preventing the said pointer 2 from being unintentionally moved out of its case. The intermediate member 12 is pivotally connected with the signal arm 2 and with the core 3' of the electromagnetic coil 3. The end portion 9 of the disk 4' catches under a piece

10 fastened to the case and suitably formed as a body which is resilient in itself. The electromagnetic coil 3 is firmly connected with the end plate 4'' of the electromagnetic coil and with a coil disk 5 of angular cross-section. The plate 5 possesses a longitudinal slit 6 into which catches an adjusting knob 7 pivotally connected with the case 8.

To the rear wall of the case 8 is fastened a contact-bar 14 which is insulated from said casing. 10 The end 13 of this contact-bar 14 is formed resilient in itself and is connected with the contact-piece of the electro-magnetic coil. The other end of the contact-bar 14 is also formed resilient in itself and leads to plug-contact to be later 15 described. The contact bar 14 is insulated from the frame and from the casing by strips 14'.

The signal arm 2 and the parts 4, 4', 4'' of the electromagnetic coil 3 and the angularly shaped end-piece 5 form a single part removably arranged in the case. For removing this part from the case the locking device 7 is turned in such a direction that it fits into the opening 6. The removable part is then at once pushed out of the case by means of the spring 13 and, unrestrained by the conducting wires, may be completely removed from the case. The signal arm together with the coil may be put in in the same easy and quick manner. For this purpose first of all the end 9 of the plate 4' is pushed under the piece 30 10, and the interchangeable part 3, 5 is then pushed into the case as far as possible so that the locking device 7 may be brought into the position shown in Fig. 1. Hereby the signal arm and the coil are secured in the case. Neither 35 during the removal nor during the installation of the signal arm together with the coil any conducting wires whatever need to be connected nor disconnected.

An insulating plug 15 is designed to be removably inserted in the metal socket 16 and secured therein by a threaded pin 16'. One of the conducting wires 15' extends through the plug 15 and is bare or headed at the upper end of the plug to form electrical contact with the contact bar 14 when the plug is in operative position. The other conducting wire 28 leads through the plug and is bare in line with the pin 16', so that when the plug is inserted to operative position it not only holds the plug in place but makes 50 electrical contact with the wire 28 to complete the other side of the circuit.

In the frame of the signal arm 2 there is provided an opening 18 for interchanging the incandescent lamp. This opening 18 may be closed.

by a slide 19 which is displaceable by means of a knob 20. An insulated contact-spring 21 is arranged inside the signal arm. Close to the opening 18 the frame of the pointer possesses a 5 perforation 22 which is connected with the opening 18. The incandescent lamp after its introduction into the pointer through the opening 18, may be pushed with its accessible end from the opening 18 into the position represented in Fig. 10 3, and, reversely, from the position shown in Fig. 3 may easily be pushed into the opening 18 and removed.

The electromagnet 3 and the signal arm 2 are connected so as to form a part removable as a 15 whole out of its case. With the upper plate 4" of the coil of the electromagnet is connected a contact-spring 23 which possesses a contact-bar 24 leading to the contact-bar 14. The contact 20 spring 23 and upper end of contact bar 24 are secured to the plate 4" by a set-screw 23' and insulated from the plate by an insulating strip 24'. To the pivot 25 by which the signal arm is 25 pivotally connected with the intermediate member 12, is fastened a socket 26 which, in the working or horizontal position of the signal arm, touches the contact-spring 23 whereby current 30 is transmitted from the conductor 15 to the incandescent lamp. During the installation and the removal of the incandescent lamp the operation is as follows:

The incandescent lamp 27 is introduced through the opening 18 and is hereby at once brought 35 into contact with the spring 21 insulated from the signal arm 2 at 21' which spring 21 makes a certain opposition to the introduction of the lamp 27 and prevents the latter from falling into the inner space of the signal arm. The lamp 27, after being pushed into this space of the signal arm 2, by its foremost part projecting from the 40 frame is then pushed laterally till this part of the lamp catches into the opening 22. The lateral motion may also be effected by the slide 19. The admission of the current to the lamp 27 is effected in well known manner. If the lamp is 45 to be replaced by a new one it is only necessary to displace the foremost part of the lamp by

hand from the opening 18 whereupon the lamp through the action of the spring 21 is pushed out of the inner space of the arm 2.

What I claim is:

1. In a direction indicator, a casing having an open side, a frame, means carried by the casing to interfit with the upper end of the frame to hold said frame in operative position within the casing, locking means carried by the casing to engage the frame for securing the frame in the 10 casing with its upper end in engagement with said means, a signal arm pivoted at its upper end to the frame, an electric conductor secured to and insulated from the casing, an electromagnet carried by the frame and means for operatively 15 connecting it to the signal arm, means carried by the frame and adapted to electrically engage said electric conductor when the frame is secured within the casing, said last named means adapted to supply current to the electromagnet, 20 an illuminating means in said signal arm, a contact arm carried by and insulated from the frame which is adapted to contact with said last means when the frame is positioned within the casing, and means carried by the signal arm to engage 25 said contact arm and complete the circuit to the illuminating means when the arm is moved to its operative position by the electromagnet.

2. A direction indicator comprising a casing having an open side, a frame, means carried by 30 said casing to engage and retain said frame in the casing, a signal arm pivotally supported by said frame and movable into and out of said casing through said open side, a solenoid carried by said frame and fixed thereto, a connection 35 between the movable member of the solenoid and the signal arm, whereby on energization and de-energization of the solenoid said movable member will move the signal arm out of and into the casing, an electric conductor extending within 40 the casing, and a second electric conductor carried by and fixed to the casing, one end of said second conductor engaging the first mentioned conductor, the other end of said second conductor being electrically connected to the solenoid. 4

OTTO KRAUS.
